HEATING APPARATUS

Art Skolas, Ida Grove, Iowa, assignor of thirty per cent to Charles L. Horn, Minneapolis, Minn., and Lee A. Horn, Ida Grove, Iowa, jointly

Application September 23, 1938, Serial No. 231,357

6 Claims. (Cl. 126—360)

The present invention relates to an oil heating apparatus having an oil burner for the clean and efficient combustion of relatively low volatile, low-grade fuel oils, and particularly to a fluid heater having such a burner.

I have discovered that low volatile, low-grade oils may be burned efficiently and cleanly in an apparatus which has no moving parts and it is therefore an object of the present invention to provide a heating apparatus free of moving parts for the clean and efficient combustion of relatively low volatile, low-grade fuel oils.

It is a further object of the invention to provide a tank heater having a burner free of moving parts for the clean and efficient combustion of low volatile, low-grade fuel oils.

It is also an object of the invention to provide a burner having provision for ready cleaning and servicing.

I have also discovered that for the efficient heating of liquids within a tank it is unnecessary to submerge the heater to the bottom of the tank and that undesirable chilling of liquids in a tank or freezing of a water tank may be prevented merely by heating the liquid near the surface. It is therefore an object of the present invention to provide a floating heater capable of floating upon the surface of a liquid for heating the liquid near the surface.

It is a further object of the invention to provide a down flame burner in combination with a heat exchanger which is adapted to be entirely submerged in the liquid of a tank, so as to give a maximum heat exchange between the device and the liquid in which it is submerged.

More specifically, it is an object of the invention to provide a stock tank heater capable of floating upon the surface of the water in the tank and capable of heating the water in the surface of the tank so as to prevent the formation of ice and for maintaining the water at a temperature suitable for stock watering.

It is a further object of the invention to provide a floating stock tank heater and a mounting for adjustably holding the heater in a floating position in the tank regardless of irregularities in inclination of the tank.

It is a further object of the invention to provide a mounting which will permit the heating unit to rise and fall with the liquid in which it is submerged.

It is also an object of the invention to provide a stock tank heater and a swivel mounting for holding the heater in a stock tank, and to provide a heater of a configuration such that it will turn bodily in the wind, all while floating in the water in the tank, so as to agitate the water within the tank and facilitate heating thereof.

It is a further object of the invention to provide a heater with a removable fuel tank for

ready refilling, and to provide a heater burner having provision for ready cleaning without the use of external apparatus.

Other and further objects of the invention are those inherent in the apparatus described, illustrated and claimed herein.

The invention is illustrated with reference to the drawings in which:

Figure 1 is an elevational view partly broken away of the fluid heater of the present invention.

Figure 2 is a partial elevational view partly in section along the line 2—2 of Figure 1.

Figure 3 is a fragmentary view partly in section along the line 3—3 of Figure 1.

Figure 4 is a fragmentary and elevational view showing the fluid heater installed in a tank and utilizing one type of bracket means.

Figure 5 is a similar and elevational view showing another type of bracket.

Figure 6 is an enlarged view partly in section of a portion of the burner apparatus.

Figure 7 is a sectional view along the line 7—7 of Figure 6.

Figure 8 is a partial elevational view of the end wall of the tank in the direction of arrows 8—8 of Figure 4.

Figure 9 is a sectional view along the lines 9—9 of Figure 1.

Figure 10 is a fragmentary view, partly in section, showing a modified form of tank mounting.

The fluid heater of the present invention is a unitary construction of such configuration and weight that it will float upon the fluid which it is to heat. The device is illustrated in Figure 1 and consists of a burner unit generally designated 10, a heat exchanger generally designated 40 and a stack section generally designated 10. The heat exchanger 40 consists of two vertical tubes 41 and 42 which are joined at their lower ends by a horizontal tube 43. These sections are preferably of steel pipe about six to eight inches in diameter and are welded along the joints 44 and 45 so as to produce a water-tight and therefore buoyant unit. At about the center of pipe section 43 there is formed a bracket generally designated 46 which is clearly shown in Figure 9. Bracket 46 consists of a strap 47 which encircles pipe section 43, which has mounted thereon a pair of arms 48. These meet and are formed with horizontal lugs 49 which are apertured as shown at 50 to receive the vertical portion of a mounting bracket as hereinafter explained. The strap 47 is preferably welded to the pipe section 43 and brackets 48 are welded to the strap 47 as shown at 51.

At the upper end of tube 42 there is mounted a stack 10 which is removably attached to the heat exchanger by means of a collar generally designated 72. The collar has a downwardly

extending flange 73 and an upwardly extending nipple 74 which receives stack 70. The latter is preferably of smaller diameter than the tube section 72 and extends upwardly about four feet or more depending upon the stack draft desired.

Between pipe section 41 and 42 there is mounted a bracket generally designated 80 having downwardly extending portions 81 which are welded to the pipe sections 41 and 42. The bracket carries a pair of upstanding lugs 82-82 upon which a fuel tank 83 is positioned. The fuel tank is not held in place except by its own weight and can therefore readily be removed as pointed out hereinafter. Tank 83 is provided with a filler opening which is normally closed by cap 84.

The oil burner portion of the heater is positioned in pipe section 41 and consists of an inner cylindrical vaporization and ignition sleeve 11 having a diameter such that there is a space 12 between it and the pipe section 41. At the upper end of the inner cylindrical sleeve there is a ring 13 and near the lower end another ring 14. In the annular space between cylinder 11, tube 41 and between rings 13 and 14 there is an insulation filler 17 such as magnesia, asbestos or rock wool.

The oil feed to the burner is by way of tube 20 which extends from the bottom of oil tank 83 laterally and downwardly to valve 21. The valve has an operating handle 22 and an outlet nozzle 23. It will be noted that the nozzle has a reduced end 24 which fits into a fitting 25. The fitting has a conical seat 26 on its upper surface which receives a similar conical face on the valve nozzle 23. The nozzle and fitting are otherwise unconnected and the entire assembly constituting tank 83, tube 20 and valve 21 may be removed from the burner unit for refilling of the tank whenever necessary. This provision precludes spilling of oil into the liquid contents of the tank in which the heater is used.

From fitting 25 there extends downwardly an oil feed line 27 which traverses the insulation 17. The tube 27 is located in the insulation so that it traverses a region of substantially constant temperature when the burner is in operation. Stated another way, when the burner is in operation there is a substantially constant temperature in the insulation from the point at which the tube 27 enters the insulation 17 to the point at the bottom of the insulation fill where the tube 27 joins cross-pipe 28. The position of tube 27 is selected so that this temperature adequately preheats the oil but does not cause any charring or carbon precipitation.

The lower end of tube 27 is connected to a cross-feed pipe 28 which extends diametrically across the inner cylindrical member 11 and thence through the outer pipe 41. The outer end of pipe 28 is provided with a cap 29 to which there is attached rod 30 as clearly shown in Figure 6. The rod 30 is of somewhat smaller diameter than the inner diameter of tube 28 and therefore provides an annular passage through which oil may flow. Rod 30 is threaded into cap 29 but is prevented from rotating by a braze weld to the cap so that as cap 29 is turned rod 30 is also turned. At the right end of rod 30, as shown in Figures 2 and 6 there is a flattened portion 31 which is of sufficient width to scrape against the inner surface of tube 28. The flattened end 31 is also shown in Figure 7. The flattened portion 31 serves not only to position the rod 30 centrally within the tube 28 but also to scrape away any

carbon which may be formed on the inner surface of tube 28 during operation of the burner. This is accomplished by simultaneously rotating and withdrawing rod 30. The rod 30 also serves to enhance the vaporizing action in the cross pipe 28 by forcing all of the oil to travel through the annular space between the rod 30 and the inner surface of pipe 28. As an example, where pipe 28 has an inside diameter of $\frac{1}{8}$ inch, rod 30 has a diameter of about $\frac{3}{8}$ inch. Thus all of the oil is forced into an annular space having a thickness of $\frac{7}{64}$ inch. The thin film of oil thus formed is quickly and uniformly heated and is readily vaporized. It is understood that this specific example is not a limitation but is merely illustrative.

At the point where tube 28 crosses the axis of sleeve 11 there is provided a T 32 which supports an upwardly extending nozzle tube 33. The tube 33 is provided with a cap 34 at its upper end immediately below which there are a plurality of orifices 35, as clearly shown in Figure 6. If desired the nozzles may be directed upwardly, or toward the air flowing downwardly through the combustion chamber. By thus directing the fuel flow against the incoming air, adequate mixing of the air and fuel is assured. The cap 34 may be removed merely by lifting it from tube 33 and when removed the upstanding nozzle tube 33 may be cleaned by the rod 30 in the same way that rod 30 is used to clean cross-pipe 28.

The upper end of tube 41 is provided with a collar generally designated 90 which is similar to that shown at 72 on tube section 42. The collar 90 has a downwardly extending flange 91 and an upwardly extending flange 92, the latter of which serves to receive the lower portion of a wind scoop 95. The wind scoop is easily removable from thimble 90 for lighting of the burner as pointed out hereinafter. At the open end of the wind scoop there is provided a damper generally designated 96, which consists of a vertical rod 97, pivotally mounted on the wind scoop and a valve 99 mounted thereon. The upper end of the rod 97 is formed with a handle 98 by means of which it may be adjusted, and a spring 100 may be provided on the rod 97 to restrain its free movement from an adjusted position. The damper 96 is ordinarily opened wide and is only closed when the unit is used in an exceedingly heavy wind.

The entire heater unit has a weight less than the buoyancy provided by heat exchanger 40 and when the oil tank is filled the unit is normally submerged to the level of line 105. As the oil is consumed by the burner the unit rises to about the level 106 which, it will be noted, is slightly above the highest point of pipe 43 of the heat exchanger.

In Figures 4 and 5 there is illustrated means for mounting the heat unit in an open tank such as a stock watering tank. In these figures the tank is illustrated at 110 and on the side wall of the tank there is provided a universally adjustable bracket generally designated 115. Bracket 115 consists of a U-bar 116 having a clamp screw 117 mounted thereon. On opposed faces of the U-bar there are welded side plates 120 and 121 which are apertured to receive a clamp bolt 122. The bolt is provided with a nut 123 and a turned-over head 124. When the bracket 115 is in place on the side of a tank the clamp bar 122 is adapted to receive a rod 125 which extends substantially horizontally to a position over the liquid in tank 110 and then downwardly to the bottom of the tank, as shown at 126. The inclination of bar

125 may be made any amount desired due to the universality of the clamp 115, and the bar 125 is therefore capable of being mounted on a tank of any shape or inclination. In Figure 5 there is illustrated another type of mounting means for supporting the burner unit. This mounting consists of a vertical rod 130 which is supported by a block of heavy material such as concrete block 131. In the mount shown in Figure 5 rod 130 has a plate at its lower end and the lower end of the rod and the plate are cast into concrete block 131. The block 131 merely rests upon the bottom of the tank and is restrained from displacement by its own weight.

The heater unit is mounted upon the vertical section of the rod (126 of Figure 4, or 130 of Figure 5) and due to the buoyancy of the unit, it floats upon the water or other liquid within the tank. As the liquid rises or falls the heater unit is free to move up or down upon the vertical section of the supporting rod and therefore the heat exchanger 40 is constantly maintained near the surface of the liquid. At the same time the heater unit is free to rotate about the vertical section of the supporting rod. In Figure 4 rotation of about 180° is possible, complete rotation being prevented by horizontal portion 125 of the supporting arm. In Figure 5 the heater unit may rotate freely around vertical rod 130.

As shown in Figure 1 it will be seen that the lateral projected area to the right of supporting bracket 46 is greater than the lateral projecting area to the left of bracket 46. In this connection it is borne in mind that stack 70 extends upwardly for a considerable distance and all of the stack area is thus presented to side wind. Thus when a side wind strikes the unit it will tend to point around the vertical supporting rod and will tend to bring the open end of wind scoop 95 directly into the wind as shown in Figure 4 or 5. The on-rush of air into wind scoop 95 tends to aid the flow of products of combustion through the apparatus, although as pointed out below under the explanation of operation of the device, the apparatus operates entirely satisfactorily in the absence of any breeze whatever. Rotary movement of the unit also facilitates heat transfer to the water or liquid in which the unit is floated.

Operation

In order to start the oil burner unit of the present invention the wind scoop 95 is removed and a small strip of cloth or bit of waste is tied around vertical nozzle tube 33. Valve 21 is then opened by rotating handle 22 and oil flows down through pipe 27 and across pipe 28 upwardly through nozzle tube 33 and finally out of orifices 35-35, and saturates the cloth or waste. If desired, a permanent asbestos wick may be applied around tube 33. After the cloth, waste or wick is thoroughly saturated with oil it is lighted and if a breeze is blowing wind scoop 95 is replaced and the unit turned into the wind to initiate the down-flow through cylindrical tube 11 across the heat exchanger 40 and thence upwardly through stack 70. If no breeze is blowing it is merely necessary to blow a breath or two of air downwardly through the tube 11 in order to force the hot products of combustion from the burning oil through the heat exchanger 40 and stack 70. Low-grade oil such as Number 3 furnace oil is used and during this preheating period the flame is smoky. As soon as the stack 70 is filled with the hot products of combustion, it initiates a draft and the downdraft through the cylinder 11

is thereafter maintained throughout the continued operation of the burner.

As the tube 33 and cross-pipe 28 are warmed vaporization begins and a clean flame is established within cylinder 11. After but a few minutes of operation cylinder 11 is brought up to operating temperature, which is a temperature somewhat above the flash point of relatively low-grade fuel oil such as Number 3 furnace oil. The temperature of cylinder 11 varies with the rate of operation but its minimum temperature is always sufficiently high to "flash" any oil projected against it, and except when operating at a very low rate, cylinder 11 is very hot, that is, it is much above ignition temperature of the oil. Cylinder 11 is preferably made of cast iron or heat-resistant steel for ordinary black iron sheet soon burns through due to the high temperature at which the cylinder operates.

The temperature attained by cylinder 11 is not greatly affected by ambient temperature of outside air or the temperature of the liquid surrounding the unit if it is submerged, since the insulation fill 17 serves to allow cylinder 11 to establish practically the same operating temperature regardless of external influences. As a consequence the burner operates as well in zero weather with the unit submerged in ice in a stock watering tank as under milder conditions.

After a few minutes of operation a temperature gradient is established through the insulation fill 17 and due to the fact that tube 27 traverses an isothermal layer of the fill 17, the fuel oil traversing pipe 27 is always preliminarily heated to a proper point for ready vaporization during operation of the burner regardless of the temperature of the oil in tank 83. The position of tube 27 in the insulation fill, the area of cross-pipe 28 which is exposed to the hot gases, and the outer area of nozzle tube 33 are made such that low-grade substantially non-volatile fuel oil such as Number 3 furnace oil is brought to a temperature which is normally slightly above volatilization temperature by the time the oil reaches orifices 35 and the fuel ejected into the down-flowing air stream through cylinder 11 is therefore for the most part in vapor form. However any droplets of fuel which may be ejected through orifices 35 are immediately vaporized by contact with the inner surface of cylinder 11, which as previously explained operates at an elevated temperature. Cylinder 11 thus acts as a vaporization and ignition cylinder.

The hot products of combustion from the burner 10 flow downwardly out of vaporization and ignition cylinder 11 into the bottom portion of vertical tube 41 and the direction of the hot gases is abruptly changed to the horizontal direction when the flow is continued through horizontal tube 43. The swirl and turbulence produced in the gases by the difference in diameter of tubes 11 and 41, by the abrupt change of direction at the junction of tubes 41 and 43 and again at the junction of tubes 43 and 42 greatly serves to enhance the heat transfer to the medium in which the unit is submerged or to outside air if the unit is used as a space heater.

Since as explained above, the unit is always maintained at the upper level of the liquid in which it is floated and an exceedingly large percentage of the heat generated by the burner 10 is therefore applied where most needed, that is to say, in heating the upper layer of the liquid. Thus when the heater is used for preventing the

formation of ice in stock tanks or for maintaining the water in stock tanks at suitable drinking temperatures only the top layer of the water is heated and as the cattle consume the warmed water the unit sinks and thus always maintains the top layer in fluid condition and relatively warm.

This feature of the invention is valuable in that it is unnecessary to heat the entire contents of a stock tank in order to provide cattle with water at proper temperature. 10

Where the unit is installed in an open tank exposed to the wind the rotation of the unit about the vertical steadyng rod 126 or 130, as the case may be, serves to enhance the heat transfer between the unit and the water in which it is floating. 15

The length of vertical pipe sections 41 and 42 may be varied, if desired, so as to bring the pipe cap 23 above the surface of the fluid in which the unit is floated. Variable weights may be added, if desired in order to vary the submergence of the unit and the shape and configuration of the heat exchanger 43 may be varied widely to meet individual conditions. Furthermore, the particular mounting illustrated herein described may be dispensed with and a hinged arm mounting provided so as to provide a vertical movement of the unit about an arcuate path which has a sufficient vertical component to take care of the rise and fall of the unit with liquid level change. Thus by pivoting an arm at one end to the unit and at the other end to the tank, with the pivot pins horizontal, adequate steadyng of the unit is provided. This type of mounting is shown in Figure 10 wherein arm 140 is pivoted to the tank 110 by means of a hinge 141 which has the hinge pin horizontal. The other end of arm 140 is hinged to the unit by hinge 142 which likewise has the hinge pin horizontal. The unit is thus free to rise and fall about the arcuate path 143 defined by the arm 140 and is prevented from tipping by the inflexibility of the arm and hinge pins to twisting movement. 20

Furthermore, where the unit is used as a space heater insulation fill 17 may be dispensed with between cylinder 11 and tube 41 and under similar conditions heat exchanger 43 may be greatly extended in view of the fact that the heat exchange to air is less than to water. These and many other obvious modifications may be made without departing from the spirit of the invention claimed. 25

It is likewise apparent that the present invention may be used as a heater for any liquid body, rather than a stock tank heater specifically, and further that the burner per se is of general application and may be used wherever an oil heater is desired. The burner need not be operated as a down-draft burner since it operates with equal facility in the horizontal or up-draft positions. 30

I claim as my invention:

1. A self-contained, floating heater unit for liquids in a tank comprising a heat exchanger having a heat exchange surface for contact with the liquid in which the device is floated, a substantially vertical rod, means for mounting said rod in a fixed vertical position relative to said tank, and means for mounting said heater unit for vertical and rotary movement on said rod. 65 70

2. A self-contained floating heater unit for

stock tanks and the like, comprising a down-draft chamber, an oil burner in said chamber, a lateral flue connected to the chamber near the bottom thereof, and a vertical stack connected to a remote end of the lateral flue, the displacement of the flue being sufficient to buoy up the entire unit when the flue is submerged, means mounting said unit for pivotal movement about a vertical axis and for vertical floating movement relative to said axis, the lateral projected area on one side of said mounting axis means being less than on the other side of said mounting axis.

5 3. A self-contained, floating heater unit for liquids in a tank comprising a heat exchanger having a heat exchange surface for contact with the liquid in which the device is floated, a substantially vertical rod, and means for mounting said heater unit for vertical and rotary movement on said rod, the entire unit being shaped so as to present a larger lateral projected area at one side of said means for mounting than on the other side of said means for mounting, whereby the unit will be turned into the direction of 15 wind blowing across said unit.

4. In combination with a stock-watering tank, a vertical guide rod, a self-contained heater for water in said tank comprising a floating unit, means for mounting said unit for vertical movement and for pivotal movement about said rod, an oil burner on the unit, a heat transfer chamber connected to said oil burner to deliver heat therefrom to the water, and a stack connected to said heat transfer unit to deliver the products 20 25 of combustion above the tank, the heat transfer unit constituting the displacement member buoying up the unit and normally submerged.

5. A floating liquid heater unit for stock tanks and the like, comprising a heat exchange flue for carrying products of combustion under the surface of liquid, a stack connected to one end of said flue, an oil burner connected to the other end of said flue, means for mounting said unit for pivotal movement as it floats, an oil supply 30 35 tank mounted on said unit, the shape and configuration of said unit being such that a larger lateral projected area is presented at one side of said means for mounting than at the other side, whereby the entire unit pivots with the wind as it floats, and an air scoop mounted on the unit in a direction toward the wind when the unit is pivoted into the wind for delivering air to said burner.

6. A floating liquid heater unit for stock tanks and the like, comprising a heat exchange flue for carrying products of combustion under the surface of liquid, a stack connected to one end of said flue, an oil burner connected to the other end of said flue, means for mounting said unit for pivotal movement as it floats, an oil supply tank mounted on said unit, the shape and configuration of said unit being such that a larger lateral projected area is presented at one side of said means for mounting than at the other side, whereby the entire unit pivots with the wind as it floats, an air scoop mounted on the unit in a direction toward the wind when the unit is pivoted into the wind for delivering air to said burner.

7. A floating liquid heater unit for stock tanks and the like, comprising a heat exchange flue for carrying products of combustion under the surface of liquid, a stack connected to one end of said flue, an oil burner connected to the other end of said flue, means for mounting said unit for pivotal movement as it floats, an oil supply tank mounted on said unit, the shape and configuration of said unit being such that a larger lateral projected area is presented at one side of said means for mounting than at the other side, whereby the entire unit pivots with the wind as it floats, an air scoop mounted on the unit in a direction toward the wind when the unit is pivoted into the wind for delivering air to said burner, and a damper for regulating the air taken by said air scoop.
